Des. 222,405
Patented Oct. 19, 1971

222,405

COMBINED WALLET AND EYEGLASS CASE

Murray Wolf, 849 Niles Road, Union, N.J. 07083

Original design application Jan. 24, 1969, Ser. No. 15,490.
Divided and this application Dec. 8, 1969, Ser. No.
20,410

Term of patent 14 years

Int. Cl. D3—02
U.S. Cl. D87—3

FIG. 1

FIG. 2

FIG. 1 is a perspective view of a combined wallet and eyeglass case showing my new design;

FIG. 2 is a side elevational view thereof opposite that shown in FIG. 1.

This is a division of design application Ser. No. 15,490, filed Jan. 24, 1969.

I claim:

The ornamental design for a combined wallet and eyeglass case, substantially as shown and described.
